UNITED STATES PATENT OFFICE.

WILLIAM SPARKS, OF JACKSON, MICHIGAN.

DESIGN FOR A SIGNAL.

45,024.

Specification for Design.

Patented Dec. 9, 1913.

Application filed August 27, 1913. Serial No. 787,036. Term of patent 7 years.

To all whom it may concern:

Be it known that I, WILLIAM SPARKS, a citizen of the United States, residing at Jackson, in the county of Jackson, State of Michigan, have invented a new, original, and ornamental Design for a Signal, of which the following is a specification, reference being had to the accompanying drawing, forming a part thereof, in which—

Figure 1 is a side elevation of a signal, and Fig. 2 is a rear plan view of the same. I claim:

The ornamental design for a signal as shown.

WILLIAM SPARKS.

Witnesses:

LILLIAN E. WUNDERLICH,
CHARLES CLINE.
